(57) **CLAIM**

The ornamental design for a pad for door stopper attachment as shown and described.

DESCRIPTION

FIG. 1 is a perspective view of a pad for door stopper attachment, showing my design;

FIG. 2 is a front elevation view thereof;

FIG. 3 is a rear elevation view thereof;

FIG. 4 is a left-side elevation view thereof;

FIG. 5 is a right-side elevation view thereof; and,

FIG. 6 is a top plan view thereof, the bottom plan view being a mirror image thereof, therefore not shown.
